Primary Examiner — Antoine D Davis(74) *Attorney, Agent, or Firm* — Schwegman Lundberg & Woessner, P.A.(57) **CLAIM**

The ornamental design for a humidity wall control, as shown and described.

DESCRIPTION

FIG. 1 is the perspective view of the second embodiment of a humidity wall control.

FIG. 2 is the exploded perspective view of the second embodiment of a humidity wall control.

FIG. 3 is the left side view of the second embodiment of a humidity wall control.

FIG. 4 is the right side view of the second embodiment of a humidity wall control.

FIG. 5 is the front view of the second embodiment of a humidity wall control.

FIG. 6 is the back view of the second embodiment of a humidity wall control.

FIG. 7 is the top view of the second embodiment of a humidity wall control; and,

FIG. 8 is the bottom view of the second embodiment of a humidity wall control.

The broken lines depict environmental subject matter only and form no part of the claimed design.
